UNITED STATES PATENT OFFICE.

OSCAR D. HAPGOOD, OF ORANGE, MASSACHUSETTS, ASSIGNOR TO GOODELL-PRATT COMPANY, OF GREENFIELD, MASSACHUSETTS, A CORPORATION OF MASSACHUSETTS.

BREAST-DRILL.

1,157,218.

Specification of Letters Patent.

Patented Oct. 19, 1915.

Application filed April 7, 1914. Serial No. 830,121.

To all whom it may concern:

Be it known that I, OSCAR D. HAPGOOD, a citizen of the United States, residing at Orange, Massachusetts, have invented new and useful Improvements in Breast-Drills, of which the following is a specification.

This invention relates to tools, and more particularly to breast drills and the like.

One of the objects of the invention is to provide a device of this character in which the driven member may be rotated at different speeds, and in which the change of speed is easily and quickly accomplished.

Another object is to provide a device of this character in which the operating parts are not liable to get out of order.

Other objects are to provide a device of this character which is compact in construction, comparatively simple and inexpensive to manufacture and which will be efficient in use.

Other objects will in part be obvious and in part be pointed out hereinafter in the claims.

In the accompanying drawings showing an illustrative embodiment of the invention and in which the same reference numerals refer to similar parts in the several figures, Figure 1 is an elevational view of a breast drill embodying the invention; Fig. 2 is a vertical sectional view on an enlarged scale; Fig. 3 is a sectional view taken on the line 3—3 of Fig. 2; Fig. 4 is a detail view of the operating handle; Fig. 5 is a sectional view thereof; Fig. 6 is a sectional view taken on the line 6—6 of Fig. 2; Fig. 7 is a sectional view taken on the line 7—7 of Fig. 2; Fig. 8 is a perspective view of a detail.

Referring to the drawings in which, by way of illustration, the invention is shown in connection with a breast drill, the drill comprises a frame consisting of two recessed members 1 and 2 adapted to house the gearing hereinafter described. The members 1 and 2 are held in position in any suitable manner, as for example, by a screw 3, and a dowel pin 4 may be provided for engaging registering recesses formed in the members by means of which they are correctly posi-

tioned with respect to one another. The upper ends of the assembled members 1 and 2 form a cylindrical projection upon which a sleeve 5 is positioned, being held in place by a set screw 6, and being provided at its upper end with a breast plate 7 of any suitable construction. The lower ends of the assembled members 1 and 2 also form a cylindrical projection which is surrounded by a sleeve 8.

Rotatably mounted in the frame is a spindle 9 provided at its upper or inner end with a bevel pinion 10 which is secured thereto in any suitable manner, and provided at its outer end with a chuck 11 which is adapted to hold the drill bit or other tool. At a point intermediate its ends the spindle 9 is provided with an annular shoulder 12 adapted to form with the lower ends of the members 1 and 2 a ball race for ball bearings 13. A suitable handle 14 is secured to the frame for holding the instrument steady in the usual manner during the operation.

Journaled in the frame is a transverse shaft 15 to which is secured a gear wheel 16 which meshes with a pinion 17 rotatably mounted upon a stud 18. The pinion 17 is secured to a gear wheel 19, which is also rotatable with respect to the stud 18, and which meshes with a pinion 20 rotatably mounted upon the shaft 15. The pinion 20 is secured to a bevel gear 21 which is rotatable with respect to the shaft 15 and which meshes with the bevel pinion 10 secured to the spindle 9. The bevel gear 21 is provided with a laterally extending annular portion 22 which encircles the shaft 15 forming therewith a sleeve or concentric shaft, the outer end of which engages an annular shoulder 23 on the shaft 15. The concentric shafts 15 and 22 are provided with recesses 24 and 25 respectively for a purpose hereinafter described.

26 indicates a crank handle which is provided with an annular portion 27 adapted to encircle the outer ends of the concentric shafts 15 and 22 and which is held in position in any suitable manner, as for example, by a set screw 28. The annular portion has

projections 27' producing a dove-tailed groove receiving the handle crank so as to fix the annular portion to the handle, while the screw 28 prevents disconnection of the parts. Rotatably mounted upon the annular portion 27 of the handle is a ring 29, the surface of which is preferably knurled or roughened, and which is provided with circumferentially extending slots 30 and 31. Within these slots are oppositely disposed cam surfaces 32 and 33, as clearly shown in Figs. 6 and 7. Extending through the slots 30 and 31 are studs 34 provided with heads adapted to engage and ride upon the cam surfaces 32 and 33 and having their lower ends connected to pawls or dogs 35 which are mounted in a recess formed in the annular portion 27 of the handle 26. These pawls 35 are normally urged inward with respect to the annular member 27 by means of springs 36, as clearly shown in Fig. 5. When the pawls occupy their innermost position they extend within the recesses 24 and 25 formed in the shafts 15 and 22, and when the pawls are in their raised position they are disengaged from their corresponding recesses, as will be evident from an inspection of Figs. 2, 6 and 7 of the drawing.

In view of the fact that the cam surfaces 32 and 33 are oppositely disposed it will be understood that as the ring 29 is rotated one of the pawls 35 will be raised by reason of the fact that the headed stud 34 connected thereto will ride upward on the surface of its co-acting cam, and the other pawl will move into its lowermost position as its corresponding headed stud 34 will ride downward upon its co-acting cam, the pawl being pressed inward through the medium of the spring 36. It will therefore be understood that when the ring is rotated in one direction one of the pawls will be caused to engage its corresponding recess and therefore lock the handle to one of the concentric shafts, while at the same time the other pawl will be moved into unlocking relation with respect to the other shaft. When the ring is moved in the opposite direction the reverse of the above takes place and the second shaft will be locked to the handle, whereas the formerly locked shaft will be unlocked with respect to the handle.

It will of course be understood that when the shaft 22 is rotated, the rotation thereof will be communicated directly to the spindle 9 through bevel gear 21 and bevel pinion 10, thus rotating the spindle 9 at its slow speed. If the shaft 15 is rotated it will rotate the spindle 9 through the train of gears 16, 17, 19, 20, 21 and 10, thus rotating the spindle at its highest speed. In order to actuate the drill at either speed it is merely necessary to position the ring 29 in such a manner that the recess of the shaft corresponding

to the desired speed will be engaged by its corresponding pawl, whereby the handle will be locked with respect to such shaft. As shown in Figs. 2, 6 and 7, for example, the parts of the drill are set for high speed, the pawl 35 being shown in locking position with the recess 24 in the shaft 15.

Having described this invention in connection with an illustrative embodiment thereof, to the details of which disclosure the invention is not of course to be limited, what is claimed as new and what is desired to be secured by Letters Patent is set forth in the appended claims:

1. In a breast drill, a frame, a spindle rotatably mounted therein, concentric shafts 80 rotatably mounted in said frame, said shafts being provided with recesses, high and low speed gears interposed with respect to said shafts and said spindle, an annulus rotatable on the shafts, a handle attached to said annulus, pawls supported by said annulus and fitting the shafts, said pawls being adapted to engage said recesses, and a ring shiftably mounted on said annulus and having oppositely acting camming surfaces for moving 90 said pawls alternately into and out of the recesses for interchangeably throwing the gears into and out of operation.

2. In a tool, in combination, a frame, a spindle rotatably mounted therein and provided at its inner end with a bevel pinion, concentric shafts rotatably mounted in said frame, a bevel gear secured to one of said shafts and meshing with said bevel pinion, a stud, a pinion and a gear wheel secured to 100 one another and rotatably mounted upon said stud, a gear wheel secured to the second of said concentric shafts and meshing with said pinion on said stud, a pinion loosely mounted on said second shaft and meshing 105 with the gear wheel on said stud, said last mentioned pinion being secured to said bevel gear mounted on said first mentioned shaft, a crank handle and means for operatively connecting said handle to either of said concentric shafts.

3. In a tool, in combination, a frame comprising recessed members and means for holding said members in position, a spindle rotatably mounted in said frame, concentric shafts rotatably mounted in said frame, inter-meshing gearing carried on said shaft housed within said recessed members and operatively connected to said shafts and to said spindle, a crank handle, and means for connecting said handle to either one of said concentric shafts for raising and lowering the speed of the spindle.

4. In a tool, in combination, a frame, a spindle rotatably mounted therein, a pinion secured to said spindle, concentric shafts rotatably mounted in said frame, inter-meshing gearing operatively connected to said

shafts and to said pinion, a crank handle, and means for operatively connecting said crank handle to either one of said concentric shafts and freeing said handle from operative connection with the other one of said concentric shafts whereby the speed of the spindle is varied.

In testimony whereof I have signed my name to this specification in the presence of two subscribing witnesses.

OSCAR D. HAPGOOD.
